UNITED STATES PATENT OFFICE.

JOHN F. OLDFIELD, OF BALTIMORE, MARYLAND.

DRY-KILN.

No. 829,732.

Specification of Letters Patent.

Patented Aug. 28, 1906.

Application filed June 5, 1905. Serial No. 263,746.

To all whom it may concern:

Be it known that I, JOHN F. OLDFIELD, a citizen of the United States, residing at Baltimore, in the State of Maryland, have invented certain new and useful Improvements in Dry-Kilns, of which the following is a specification.

This invention relates to a drying-kiln.

The object of the invention is to improve kilns of that class where the material to be dried rests on trucks which are run into the kiln, the drying operation follows, and then the trucks are run out of the kiln, whereby the time required for operation of drying will be shortened.

The invention is illustrated in the accompanying drawings, in which—

Figure 1 is a vertical cross-section of a dry-kiln house, showing one form of the invention. Fig. 2 is also a vertical cross-section of a dry-kiln house, showing a modified form of the invention. Fig. 3 is a vertical longitudinal section of the dry-kiln.

This dry-kiln may be used for drying or evaporating water from any material, but is intended principally for drying green lumber. The operation involved in this kiln is the action on lumber of hot humid circulating air under slight pressure, which air in the course of its circulation is repeatedly reheated, whereby a moist temperature considerably exceeding the boiling-point of water is maintained.

Referring to the drawings, Fig. 1, the walls A may be made of any material. In the drawings they are shown made of wood. In the space between the internal sheathing b and the external sheathing b' is a suitable heat-insulating material c. The bottom and its connection with the walls is tight. The roof D may have any preferred construction. Spaces or openings g' of some kind are provided for the escape of steam. The ceiling or top E is tight and has heat-insulating material similar to the walls, but is provided with central vents or openings g for the escape of steam from the drying-chamber B.

Heretofore dry-kiln houses have had vertical passages or ducts formed in or against the walls, with the upper ends of the passages opened at and communicating with the top of the drying-chamber, and the lower ends opened below the heater on the bottom. In operation the hot moistened or saturated air passes from the top of the drying-chamber down these passages or ducts.

I found by observation that in kilns thus constructed, where the escape of saturated air was at the top of the drying-chamber into the said down passages or ducts, the lower portion of the pile of lumber that was being dried in the chamber was always the last to become dry and that the time required to dry a truck-load—say five thousand feet—of soft wood, one-inch green lumber just from the saw, was about forty-eight hours.

As a result of experimentation I have found that by providing for the escape of the saturated air from the drying-chamber into the down passages or ducts at a point about midway of the height of said chamber, instead of at the top, as heretofore, the time required for the operation of drying is very materially reduced, and that where forty-eight hours was required by the old construction less than twenty-four hours is required by the new construction.

Down passages or ducts I of ample size are formed on each side wall of the dry-kiln chamber B. The upper ends i' of these passages are open or communicate with said chamber at a point whose vertical position is about midway between ceiling E and the track-rails F. The lower ends i'' of the passages open below the heater or steam pipes p. By thus arranging the top opening of the vertical passages or ducts about half-way up on the side walls of the drying-chamber the operation of the drying-chamber is greatly improved, because the circuit within which the hot humid air circulates is shortened. Consequently the circulation is more rapid. The lumber on the truck dries all over with equal rapidity, and the time required for drying is reduced one-half or more. This feature of vertical ducts with a short circuit may be used with or without a hooded ceiling in the chamber. In Fig. 1 the hooded ceiling is shown. It comprises a tight inner ceiling or false ceiling H below the outer or uppermost ceiling E, with a space k between the two, the inner sides H' depending from said inner ceiling and extending downward along the side walls of the chamber. The distance downward to which they may depend may vary; but said depending inner side must not extend down so as to cover the upper openings i' of the down passages or ducts. The inner sides H' are spaced away from the internal sheathing b of the side wall, and thereby form narrow passages or ducts l for the escape of reheated moisture. These moisture-escape

passages *l* communicate with the space *k* at the top and are relatively smaller in size than the down-passages *I*, which difference in size contributes to the proper operation of the drying-kiln.

When the reheated moisture reaches the space *k*, it passes therefrom through the vent *g* under the roof and thence out at *g'*.

The air-tight ceiling, with depending sides tightly attached, forms a hood or tight cover within the top of the drying-chamber. Moisture or steam is confined by this hood and can escape from the drying-chamber only at the lower edge of the said depending sides where the opening *l'* to the up-passage is found. By this combination the former operation of this class of dry-kiln is modified. First, the hood retains the hot moisture at the top and around the upper part of the pile of lumber until it becomes excessive and creates a pressure and then it escapes at the openings *l'* of the up-passages; second, the circulating and reheating goes on through the short circuit.

In the operation of this kiln no provision is made either for admitting or expelling air. When the moisture within the kiln reaches its highest attainable temperature, which will considerably exceed the boiling-point of water, the pressure thereby created finds relief at the vent-opening *g* in the top.

Referring now to Fig. 2, it may be stated the construction is exactly the same as in Fig. 1 except that in Fig. 2 the hooded ceiling is absent. The more rapid circulation because of the short lower circuit is the same, and the only difference is that the reheated moisture escapes directly from the drying-chamber *B* through the vent *g* instead of indirectly, as by the up-passages in Fig. 1.

Having thus described my invention, what I claim as new, and desire to secure by Letters Patent, is—

1. A dry-kiln structure having walls and bottom tightly connected; a roof; a drying-chamber; a ceiling between the drying-chamber and roof and provided with a vent-opening communicating between the chamber and the space under the roof; a heater appa-

ratus near the bottom of the chamber; and a short circuit for the circulation of hot humid air, said circuit comprising passages or ducts, *I*, whose highest ends, *i'*, open from the drying-chamber at a point half-way up its vertical dimension and whose lowest ends open to said chamber below the said heater apparatus, as set forth.

2. A dry-kiln structure having walls and bottom tightly connected, and a roof; a ceiling and sides tightly joined thereto and depending downward within the walls of the structure—said depending sides forming vertical escape-passages whose openings from the drying-chamber are at the lower edge of said depending sides and lead therefrom to the space above the ceiling; a heater apparatus near the bottom of the chamber; and a short circuit for the circulation of hot humid air—said circuit comprising passages or ducts whose highest ends open from the drying-chamber below the lower ends of said escape-passages, and whose lowest ends open to said chamber below the heater apparatus, as set forth.

3. A dry-kiln structure having walls and bottom tightly connected, and a roof; a ceiling and sides tightly joined thereto and depending downward within the walls of the structure; a drying-chamber having upward-escape passages whose lowermost openings are approximately half-way between the said bottom and ceiling; a heater apparatus near the bottom of the chamber; and a short circuit for the circulation of hot humid air—said circuit comprising passages or ducts of size relatively larger than the said escape-passages and whose highest ends open from the drying-chamber below the lower ends of said escape-passages, and whose lowest ends open to said chamber below the heater apparatus, as set forth.

In testimony whereof I affix my signature in presence of two witnesses.

JOHN F. OLDFIELD.
